[57] **ABSTRACT**

A garment hanger of the coat hanger type comprising

9 Claims, 6 Drawing Figures

a wire formed into a triangular body having a hook extending upwardly from the apex of the triangle. The hanger disclosed herein is designed to be formed by machine without twisting so as to minimize the amount of wire needed without sacrificing strength and rigidity. The hanger is characterized by a length of wire, preferably continuous, bent into triangular shape with an elongated medial run extending across the full width of the hanger to form the stretcher of the triangular body. Side elements of the wire converge from the ends of the stretcher toward the apex of the body and terminate in connecting pieces, one of which nests neatly within the other, all within the same plane. The piece remote from the stretcher run extends outwardly to constitute the hook of the hanger. In the preferred embodiment, the connecting pieces are U-shaped and the bases of the nesting pieces are fastened into abutting relation throughout their length by a clip in the form of a split sleeve. In a modified embodiment, the bases of the U-shaped connecting pieces are united in abutting relation along their length by welding or the like.

Fig. 1***Fig. 2******Fig. 4******Fig. 3******Fig. 5***

Fig. 6

GARMENT HANGER

The present invention relates to garment hangers and particularly relates to coat hangers formed from wire in the general configuration of a triangle having a hanger hook at the apex thereof.

The wire coat hanger manufactured in the greatest quantity today consists of a one-piece structure having the wire formed into a generally triangular outline and having the hook connected to the apex of the triangle by a shank. The wires from the side elements of the triangle are twisted together along the shank. To reduce the danger of snagging the clothing on the free ends of the wire portions, the raw ends may be coated or sheathed or inserted within tubular elements. With the conventional construction, these protective operations must be performed after the wire is formed and assembled into its final configuration. It has been found that the conventional hanger entails substantial waste, not only in the use of additional length of wire to provide a firm interconnection by twisting, but also in the losses in manufacturing which arise due to the breakage of the wire during twisting. Such waste entails an increase in the manufacturing cost which affects the unit cost of each hanger. Attempts to conserve wire by using a wire of a smaller gauge or thickness have resulted in hangers of considerably less strength which become distorted beyond use in normal handling operations. Since wire coat hangers are purchased by dry cleaning establishments for a single use within the establishment, a small reduction in the "per unit" cost entails a considerable saving in annual operating costs of the establishment.

With the foregoing in mind, the present invention provides a coat hanger which utilizes less wire than the conventional hanger and yet is stronger and more durable. The present invention provides a hanger which not only has a pleasing appearance but also positions the raw ends of the wire so as to avoid snagging the clothing placed on the garment hanger. The form of the hanger, which eliminates crossovers of the wire forming the body of the hanger, facilitates stacking and storing of the hangers inasmuch as the body wire of the hanger is coplanar throughout.

The invention also provides a hanger which is formed by simple bending operations (without twisting) which minimizes loss during the forming operation and may also permit prepainting of the wire prior to forming. The invention also contemplates a novel method of forming a hanger which entails simple bending operations to form the hanger and a single fastening operation to complete the assembly. The fastening operation may consist of welding or wrapping around a clamping sleeve, either of which is performed in a zone of the assembled hanger which provides a relatively straight run for reception of the clamping sleeve or the weld.

All of the objects of the invention are more fully set forth hereinafter with reference to the accompanying drawings, wherein:

FIG. 1 is a face view of a hanger made in accordance with the present invention;

FIG. 2 is an enlarged fragmentary view of the hanger shown in FIG. 1 more clearly illustrating the construction of the hanger;

FIG. 3 is a transverse sectional view taken on the line 3-3 of FIG. 2 at an enlarged scale;

FIG. 4 is a view similar to FIG. 2 of a modified embodiment of the hanger made in accordance with the present invention;

FIG. 5 is an enlarged transverse sectional view taken on the line 5-5 of FIG. 4 and illustrating schematically a method for completing the assembly of the hanger of FIG. 4; and

FIG. 6 is a view similar to FIGS. 2 and 4 illustrating a further modified embodiment of the hanger made in accordance with the present invention.

Referring to FIG. 1, the hanger 14 illustrated therein comprises a single length of wire forming both the triangular body of the hanger 14 and the hook element. The wire is formed into a circular bight or loop 15 which terminates at one side in a raw end 15a and at the other side in a suspension run 16. The run 16, as shown in FIG. 2, merges into a connecting piece having a generally U-shaped form with laterally-spaced legs 17 and 18 and an intermediate base 19. At the side of the piece remote from the suspension run 16, the leg 18 merges into a side element 22 which diverges outwardly, forming one side of the triangular body portion and terminating at the outer end of a stretcher run 23 forming the bottom of the triangular body portion. The other end of the stretcher run 23 merges into an opposite side element 24 which terminates at its upper extremity in a connecting piece of generally U-shaped form adapted to nest with the other connecting piece and having, as shown in FIG. 3, laterally-spaced legs 25 and 26 with an intermediate base 27. As shown in FIG. 2, the leg 26 has a free end 26a which is positioned intermediate the leg 18 and the side piece 22.

The connecting pieces at the apex of the triangular body portion nest within each other so that the base 19 abuts flush against the base 27 along the length thereof. The base 19 may be considered a portion of the exterior connecting piece and the base 27 may be considered a portion of the interior connecting piece. Preferably all of the components of the hanger 14 are coplanar. The base portions 19 and 27 are parallel to one another and are preferably generally parallel to the stretcher run 23 and serve to connect the side runs 22 and 24 to each other at the apex of the triangular body to complete the body.

In this embodiment of the invention, the nesting connecting pieces are united in flush abutting relation by a clip in the form of a split sleeve 31 having sidewalls 32 and 33 which bear tangentially against the coplanar base portions 19 and 27 (see FIG. 3). The top wall 34 of the sleeve 31, in the present instance, is continuous and bears against the exposed side of the base portion 19 in the exterior connecting piece and the bottom wall of the sleeve 31 is split lengthwise to form inturned toes 35,35 which engage under the exposed underside of the base portion 27 of the interior connecting piece. In this fashion the toes 35 cooperate with the endwall 34 to maintain the base portions 19 and 27 in parallel adjacent relationship along the length thereof, preventing lateral separation of the connecting pieces in the vertical direction within the plane defined by the wires. When clamped together in this fashion, the legs of the nested connecting pieces prevent relative longitudinal displacement of the connecting pieces in a direction axially of the sleeve 31. The sidewalls 32 and 33 engage flush against the sides of the nesting connecting pieces not only to prevent bodily transverse separation of the pieces out of the plane of the hanger wire but also to resist distortion of the connecting pieces by torsional

forces, for example created by twisting the loop and its suspension run 16 either about a vertical axis within a plane of the hanger wire or about a horizontal axis generally coincident with the axis of the sleeve 31.

Furthermore in this embodiment of the invention, the loop 15 has a center of curvature designated at 36 which is disposed on the vertical centerline 37 of the hanger. The vertical centerline 37 of the hanger coincides with the perpendicular bisector of the axis of the sleeve 31 and the bisector of the apex of the triangular body, so that the hanger tends to hang straight when suspended on a rod or other support. It should be noted that an additional degree of stability is provided to the hanging hanger by reason of the angular traverse of the suspension run 16 transversely across the centerline 37 intermediate the hook 15 and the exterior connecting piece leg 17.

As clearly shown in FIG. 2, each of the bases 19 and 27 has a straight portion between the legs about which the sleeve 31 is clamped. The endwall 34 and the toes 35 of the straight tubular sleeve 31 preferably engage flush against the straight portions throughout the length of the clip and endwise displacement of the sleeve relative to the nested bases is resisted not only by the clamping actions of the toes against the base portion, but also by the legs of the connecting pieces at either end of the sleeve.

This embodiment of the invention is especially adapted for fabrication and assembly by machine in an automated fashion. To this end, the bends and curves imparted to the wire may be performed by machine either simultaneously or in sequence. In the method of fabricating the hanger, the wire is bent to the desired triangular body portion of the hanger including the connecting pieces. The pieces are then brought into coplanar nesting relationship and are fastened together in parallel adjacent relationship, preferably so as to abut the bases 19 and 27 flush against one another along their length. While maintained in nesting coplanar relation in the preferred embodiment, the clamping sleeve is applied and clamped upon the base portions so that they are prevented from lateral separation in the plane of the hanger by the cooperative action of the endwall 34 and the toes 35. During the fabrication, the suspension run 16 and the hook 15 are also formed, either concurrently with the triangular body or separately.

The clamping sleeve may be a decorative element if desired since the wire may be prefinished by coating or other surface treatment prior to forming it into the triangular body and thus the hanger may be ready for use at the completion of the clamping operation without the need for further finishing procedures, bearing in mind that the raw ends 15a and 26a of the wire are positioned to avoid engagement with the garments to be placed on the hanger.

It may be desirable to fasten the connecting pieces together in their coplanar nested relationship by means other than a surrounding tubular sleeve, as shown at 31 in FIG. 2. Depending upon the machine capabilities, the connecting pieces may be united by soldering, brazing or cementing. A preferred alternative is to unite the pieces by welding them, as shown in FIG. 4. To this end the wire forming the hanger is formed identically to that shown in FIG. 1 including a hanger bight 115, a suspension run 116, and exterior connecting piece with legs 117 and 118 spanned by a base run 119. A sidepiece 122 extends from the leg 118 and a complemen-

tary sidepiece 124 terminates in a nesting interior connecting piece having legs 125 and 126 with an intermediate base run 127. As shown in FIG. 4, the base runs 119 and 127 are welded together as indicated at 131. A welding operation is preferred since it may be performed by spot welding apparatus as illustrated diagrammatically in FIG. 5 wherein the welding apparatus includes clamping jaws 134 and 135 which not only apply the welding potential to the wire portions 119 and 127 but also serve to clamp the portions into flush abutment throughout their length. This spot welding operation is enhanced by reason of the straight character of the base portions 119 and 127 so that a strong and rigid connection is provided. Since a precoating of the wire might interfere with the efficient welding operation and may preclude flush engagement of the wire portions, in this embodiment of the invention it is preferred to coat the wire following the welding operation, if it is desired to have a coating on the wire. On the other hand, if it is desired to incorporate bare wire into the hanger, no further treatment is necessary, although it may be desired to cover the weld by a decorative sheath or wrap.

A further modification is shown in FIG. 6 wherein the bends and curves in the wire are less severe than those in the wire of the hangers in FIGS. 2 and 4. To this end the wire of the hanger in FIG. 6 starts at an end 44 and is formed into a bight or loop 45 which merges into a suspension run 46. At the opposite end of the suspension run 46, an exterior connecting piece is provided having legs 47 and 48 interconnected by a curved base 49. The leg 48 continues into a sidepiece 52 which corresponds to the sidepiece 22 of the embodiment of FIG. 1. The complementary sidepiece 54 from the other end of the stretcher run terminates in an interior connecting piece having legs 55 and 56 extending upwardly from the intermediate curved base 57. The connecting pieces nest one within the other as shown so that the curved based portions 49 and 57 are disposed in parallel adjacent relationship, in this case, like the previous embodiment, engaging flush against one another throughout their lengths. A straight connecting sleeve 61 is provided to engage around the bases 49 and 57 in a manner similar to the way in which the sleeve 31 engages around the bases 19 and 27. In this embodiment of the invention, the vertical centerline of the hanger is shown at 67 and the center of curvature of the bight 45 is positioned on the vertical centerline as indicated at 66. The sleeve 61 is also positioned on the centerline 67 as shown so that the perpendicular bisector of the sleeve axis coincides with the centerline 67.

The curved bases 49 and 57 preferably have a common center of curvature 68 which coincides with the vertical centerline 67 as shown. In order to insure a firm clamping action between the curved base portions 49 and 57, the radius of curvature should be preferably at least three times the axial length of the sleeve 61 as indicated by the designations 3X and X respectively in FIG. 6. As the radius of curvature increases, the configuration of the connecting pieces approaches the configuration of the connecting pieces shown in FIGS. 2 and 4. In the illustrated embodiments, the base portions of the connecting pieces, whether they be slightly arcuate as shown in FIG. 6 or perfectly straight as shown in FIGS. 2 and 4, are disposed substantially parallel to the stretcher run of the triangular body of the hanger at the apex of the side elements. In the preferred embodiment of FIGS. 2 and 6, the sleeve is split along the interior

endwall thereof as indicated at 35,35 in FIG. 3. Of course, the split may be positioned on the exterior endwall, or one of the side walls as desired. The embodiment of FIG. 6 has many of the functional and operational advantages of the embodiments shown respectively in FIGS. 2 and 4, and may be preferred in order to accommodate the formation of the hanger to certain machine operations available to the manufacturer.

While particular embodiments of the present invention have been herein illustrated and described, it is not intended to limit the invention to such disclosures but changes and modifications may be made therein and thereto within the scope of the following claims.

I claim:

1. A garment hanger composed of a single continuous-length rigid wire of uniform cross-section formed into a generally triangular body portion with suspension means extending outwardly from the apex of the triangle, the triangle having side element converging toward the apex and having a stretcher run extending between the remote ends of said side elements, the improvement wherein said side elements are formed from the wire, each side element terminating at the apex in a U-shaped connecting piece having a pair of spaced-apart legs interconnected by an intermediate base portion, the connecting pieces of the two side elements nesting one within the other at the apex of the triangular body portion with the base portions thereof disposed flush against one another in a line along the length thereof, said connecting portions being all coplanar with said side elements and positioned in nesting relation without crossovers, said base portions when in nested relation serving to complete the triangular body intermediate the side elements, the connecting piece more remote from the stretcher run being on the exterior side of the body, and the other connecting piece being on the interior side of the body, the wire at the far end of said exterior connecting piece opposite its associated side element being formed into an open suspension hook projecting from the triangular body portion within the plane of said body portion, the wire at the far end of the interior connecting piece terminating closely adjacent the side element associated with the exterior connecting piece, and uniting means positioned intermediate said spaced-apart legs uniting said base portions in nested relation along the length thereof to prevent lateral or transverse separation of the connecting pieces.

50

2. A garment hanger according to claim 1 wherein the base portions of said connecting pieces are straight and disposed parallel to the stretcher run on the centerline of the hanger so that the centerline coincides with the perpendicular bisector of the base portions, said suspension hook having a curved portion with a center of curvature also coinciding with the centerline of the hanger.

3. A garment hanger according to claim 2 wherein said hook is connected to said exterior connecting piece by a suspension run of said wire, said hook and suspension run being coplanar with said triangular body portion, said suspension run being straight and disposed to traverse said centerline of the hanger at an angle.

4. A garment hanger according to claim 1 wherein said uniting means consist of a separate fastening element clamping the base portions in said flush abutting relation along the length thereof intermediate the legs of the connecting pieces.

5. A garment hanger according to claim 4 wherein said fastening element comprises a straight tubular sleeve having an axial split therealong, said sleeve bearing against said base portions to anchor the same against relative displacement out of the plane of the hanger body as well as displacement within the plane of the hanger body, the legs of the nested U-shaped pieces cooperating with the ends of said sleeve to prevent relative longitudinal displacement of said pieces axially of said tubular sleeve.

6. A garment hanger according to claim 5 wherein said sleeve has sidewalls bearing against the sides of the base portions of both connecting pieces and endwalls respectively bearing against the exposed interior and exterior surfaces of the bases, the split of said sleeve being positioned in one of said endwalls to provide complementary toe portions said toe portions cooperating with the other of said endwalls to clampingly engage said base portions together.

7. A garment hanger according to claim 1 wherein said uniting means comprises a welded connection along the line of flush abutment of the base portions of said connecting pieces.

8. A hanger according to claim 1 wherein said base portions are straight throughout the length of said uniting means.

9. A hanger according to claim 1 wherein said base portions have a curvature with a radius at three times the length of the uniting means.
